United States Patent Office.

ROBERT ROBERTS, OF ST. PAUL, INDIANA.

Letters Patent No. 70,618, dated November 5, 1867.

IMPROVED SPRING-BEDSTEAD.

The Schedule referred to in these Letters Patent and making part of the same.

TO ALL WHOM IT MAY CONCERN:

Be it known that I, ROBERT ROBERTS, of St. Paul, in the county of Decatur, and State of Indiana, have invented a new and useful improvement in Spring-Bedsteads; and I do hereby declare that the following is a full, clear, and exact description of the same, reference being had to the annexed drawings, making part of this specification, in which—

Figure 1 is a perspective view, and

Figure 2 is a vertical longitudinal section.

The same letters are employed in both figures in indicating the same parts.

A is the frame of the bedstead. Angles formed from metallic plates or other convenient material are attached to the corners at B, for the purpose of supporting the frame C, upon which the spiral springs D rest, along each side of the bedstead. On the springs D are placed the bars E, crossing the bedstead, and pressed by the springs D against the under face of the cleats F, which are attached by screws to the side rail of the bedstead.

To adapt this bedstead to use as an invalid-bed, the end G is made with a frame enclosing the springs, and hinged to the inner frame C by hinges H, fastened to the upper face thereof, so that the entire head-piece may be elevated to any desired angle, and there held by the hinged legs K, resting adjustably against the rack K'. A cord, L, is passed through the head-piece, and fastened to the legs K, so that they may be turned up when it is desired to lower the head-piece from the outside edge of the bed. Bands of webbing, I, are fastened to the bars E, to hold them in place, being attached to the top of all the bars except the lower one of the hinged bed-piece, under which it is passed, and fastened to the foot-board by eyes, or in other convenient manner. The springs, &c., may be conveniently removed by detaching the side rails F and the webbing from the foot-board, and then lifting out all the other parts with the frame-pieces C.

Instead of the means set forth herein for supporting the springs, I contemplate using horizontal flat strips attached on the inner face and at the bottom of the side rails, upon which the springs may stand, the width of the rails being such as to bring the level of the cross-slats below that of the top of the rails. And instead of the webbing, as set forth, cords may be used for fastening together the said slats.

What I claim as my invention, and desire to secure by Letters Patent, is—

1. In combination with the bedstead A, supports B, and cleats F, the frame C, springs D, slats E, and webbing I, arranged substantially as and for the purpose set forth.
2. The head-piece G, when attached by hinges to the inner and detached frame C, substantially in the manner set forth.
3. The combination of the slats E, springs D, webbing I, and hinged head-piece G, arranged substantially as set forth.

In testimony whereof I have signed my name to this specification in the presence of two subscribing witnesses.

ROBERT ROBERTS.
